APPARATUS FOR PREVENTING INCRUSTATION IN STEAM BOILERS

Original application filed October 17, 1921, Serial No. 508,171, and in Argentina April 11, 1923. Divided and this application filed August 21, 1923. Serial No. 658,509.

This invention relates to an apparatus for preventing the incrustation of boilers and is particularly adapted to carrying out the method disclosed in my co-pending application Serial No. 508,171 filed October 17, 1921, of which application this application is a division.

The apparatus includes, broadly, means which operates in conjunction with the steam 10 from the boiler to generate the mucilaginous substance and means by which said substance may be conducted to and introduced into the boiler.

I have illustrated in the drawing one form 15 of apparatus by means of which the method may be carried out but it is to be understood that the invention is not limited to that form of apparatus as many modifications may be made in the construction.

20 In the drawing:

Figure 1 is an elevation of the selected embodiment showing the same mounted on the boiler, the boiler being conventionally illustrated;

25 Figure 2 is an enlarged elevation partly in section showing the relationship of the various parts;

Figure 3 is a top plan elevation partly in section;

30 Figure 4 is a sectional view disclosing the interior perforated cylinder in which the mucilaginous substance is generated; and

Figure 5 is a top plan view of said perforated cylinder.

35 The selected illustrative embodiment of the apparatus includes a cylinder 1 having circumferentially radiating ribs or fins thereon. This cylinder 1 has communication with the boiler, the incrustation of which is to be

40 prevented, through a pipe 2 which extends from adjacent the upper end of the cylinder to the steam space of the boiler and is provided with a manually operable valve 3 by means of which the steam from the boiler may be

45 permitted, at the desired intervals or continuously, to enter the cylinder. Communication is established between the lower end of the cylinder and the boiler by means of a pipe

40 which pipe extends below the water line of the boiler and is provided with a manually

operable valve 5. The upper end of the cylinder is closed by suitable means which, in the embodiment selected for illustration, includes a plate 6 having a flange and groove engagement with the upper edge of the cylinder. This plate 6 is held in tight engagement with the upper edge of the cylinder to seal the latter by means of a yoke 7 and bolts 8 which extend through the yoke and are adapted to force the plate downwardly onto the upper edge of the cylinder.

This plate 6 is provided with a blow-off valve 9 through which communication is established between the interior of the cylinder 1 and the atmosphere.

A perforated cylinder 10 having a removable cover 11 with a yoke 12 thereon at one end and a similar cover 13 with a yoke 14 thereon at the other end, is mounted within the outer cylinder 1. These covers 11 and 13 are held in place on the cylinder 10 by a tie rod 19 which extends through the cylinder and the yokes 12 and 14 and is provided with tightening nuts which abut against the yokes 12 and 14.

A perforated tube 18 is arranged within the cylinder 10 and extends axially from end to end of said cylinder, the upper end of the tube extending preferably through the cover 11 and the lower end abutting against the cover 13. This latter cover is provided with an opening 16 having a flange 17 extending upwardly into the tube 18 to position the latter, through which opening communication is established between the tube 18 and the chamber 15 at the lower end of the cylinder 1, from which chamber the pipe 4 extends. It will be noted that the cylinder 10 rests upon the annular shoulder at the lower end of the cylinder 1, thus isolating the chamber 15 from the remainder or upper portion of said cylinder, and closely fits the upper portion of the cylinder but that surrounding the inner cylinder is a space defined by the wall of the cylinder 10 and the interior face of the ribbed portion of the cylinder 1. In the cylinder 10 is located the material from which the mucilaginous substance is generated.

I have found that vegetable seeds such as flax, hemp, or similar seeds may be used en-

tirely successfully and I contemplate in certain instances the use of soda which may be mixed with the seeds to soften the husks of the same to facilitate the extraction of the gluten contained by the seeds. Furthermore, 5 I have found that the use of fecula (starch) assists in the formation of the desired mucilaginous substance. A mixture of vegetable seeds, soda, and starch wherein the soda is equal to about one one-hundredth of and the 10 starch to about one two-hundredths of the weight of the seeds I have found produces the desired result. It is of course to be understood that I contemplate the use of the 15 vegetable seeds either with or without the soda starch.

In operation, the vegetable seeds or the mixture of vegetable seeds, soda and starch having been placed in the perforated cylinder 10, the valve 3 is opened permitting steam from the steam space of the boiler to enter the condensing cylinder 1. The steam entering the cylinder 1 fills the latter and is condensed because of the radiation afforded by the ribs 20 or fins thereon and the condensed steam passes into the cylinder 10 through the perforations therein. This condensed steam on coming in contact with the vegetable seeds takes up the mucilaginous substance from the seeds and produces an emulsion but does not extract the oily compounds from the seeds which of course are injurious to steam boilers. The emulsion thus formed passes, upon the 25 opening of the valve 5, which opening may either be periodic or continuous, through the pipe 4 to the water of the boiler. The emulsion mixed with the water of the boiler envelops the nascent saline deposits which result from the evaporation of the water within 30 the boiler and sinks with the deposits to the bottom of the boiler from which position removal may conveniently be carried out.

Of course, it is to be understood that the introduction of the mucilaginous substance 35 into the water of the boiler not only prevents the formation of fresh incrustations but also removes the incrustations which have already been formed on the walls of the boiler and that the method and apparatus may be 40 successfully employed in either boilers using fresh or sea water.

While I have described a particular form 45 of apparatus by means of which the method may be carried out, it is to be understood that this apparatus may be varied in its details 50 of construction without departing from the spirit of the invention or exceeding the scope of the claims.

What I claim is:

60 1. The combination with a steam boiler of a container a mucilaginous substance arranged in a hollow column in said container, means for conveying steam from the boiler above the water level thereof to the interior 65 of said hollow column of mucilaginous sub-

stance, means for effecting the condensation of the steam, means for permitting the water of condensation to pass through the mucilaginous substance, and means for conveying the water of condensation from the container to the boiler below the water line thereof. 70

2. The combination with a steam boiler of a container having radiating means thereon, a body of mucilaginous bearing substance within said container, means for conveying steam from above the water level of the boiler to and through the mucilaginous bearing substance, means for condensing the steam which passes through the mucilaginous substance, and means for permitting the passage of the water of condensation from the condensing means to said last mentioned means through the mucilaginous bearing substance. 75

80 3. In a device of the class described the combination with a container having a steam inlet pipe at the top thereof and a water outlet pipe at the bottom thereof of a cylindrical perforated receptacle mounted within the container and having a centrally perforated core, the said container having a condensing space surrounding the receptacle which space is inaccessible to the inlet and outlet pipes except through the receptacle, and a mucilaginous bearing substance arranged within the receptacle whereby the steam entering through the central core thereof will penetrate said substance, pass to the condensing space, and the water of condensation will pass through the mucilaginous substance into the central core to the water outlet pipe. 85

90 4. In a device of the class described the combination with a container having an annular condensing space in the inner wall thereof and an outlet space at the bottom thereof, of an inlet space at the top thereof, a steam inlet pipe communicating with the top space, a water outlet pipe extending from the bottom space, a receptacle mounted within the container isolating the top and bottom spaces from the condensing space except through the receptacle, the said receptacle having perforations in the wall and in the top and bottom thereof. 100

105 5. In a device of the class described the combination with a container having an annular condensing space in the inner wall thereof, an inlet space at the top thereof and an outlet space at the bottom thereof, of a steam inlet pipe communicating with the top space, a water outlet pipe extending from the bottom space, a receptacle mounted within the container isolating the top and bottom spaces from the condensing space except 110

115 through the receptacle, the said receptacle having perforations in the wall and in the top and bottom thereof, and a perforated central core opening at the top and bottom thereof into top and bottom spaces of the container arranged within said receptacle. 120

125 6. In a combination of the class described 130

- the combination with a container of a receptacle mounted therein, said container having a steam inlet at the upper end thereof and a water outlet at the lower end thereof, a 5 mucilaginous bearing substance in said receptacle, said receptacle being constructed and arranged within the container in such manner that the steam entering the upper end of the container must pass through the mucilaginous substance in said receptacle, prior to 10 its reaching the water outlet pipe, and means for condensing the steam in its passage from the inlet to the outlet. 7. In a device of the class described the combination with a container having a steam inlet pipe at one end thereof and a water outlet pipe at the other end thereof, a perforated receptacle mounted within the container and having a perforated core therein, the 15 said container having a condensing space between its wall and the receptacle which space is inaccessible to the inlet and outlet pipes except through the receptacle. 8. In a device of the class described the combination with a container having a condensing space in the inner wall thereof, an inlet space at the top thereof of a steam inlet pipe communicating with the top space, a water outlet pipe extending from the bottom 20 space, a receptacle mounted within the container isolating the top and bottom spaces from the condensing spaces except through the receptacle, the said receptacle having perforations in the wall and in the top 25 thereof. 9. In a device of the class described the combination with a container having a condensing space in the inner wall thereof, an inlet space at one end thereof and an outlet 30 space at the other end thereof, of a steam inlet pipe communicating with the inlet space, a water outlet pipe extending from the outlet space, a receptacle mounted within the container isolating the inlet and outlet spaces 35 from the condensing space, the said receptacle having perforations communicating with the condensing space, and a perforated central core communicating with the inlet space and with the receptacle. 10. In a device of the class described the combination with a container having a steam inlet pipe at one end thereof, a water outlet pipe at the other end thereof, a perforated receptacle mounted within the container and 40 having a perforated core therein, the said container having a condensing space between its wall and the receptacle, and means for conducting water of condensation from the condensing space to the water outlet pipe. 11. In a device of the class described, the combination with a container of a receptacle mounted therein, said receptacle containing a mucilaginous bearing substance and having a chamber extending substantially from end 45 to end thereof, means for conducting steam to 50 said chamber whereby the steam is permitted to pass into the said mucilaginous substance throughout substantially its extent and through the substance to the condensing space, and means for conducting the water 55 of condensation from said condensing space. 70 In testimony whereof, I have signed my name to this specification this 6th day of August, 1923. 75 JOAKIME KOBSEFF. 75
